(57) **CLAIM**

We claim the ornamental design for a magnifying lens, as shown and described.

DESCRIPTION

FIG. 1 is a front perspective view of a magnifying lens according to the present invention shown mounted to an LED light stand;

FIG. 2 is a front perspective view of the magnifying lens;

FIG. 3 is a left side view thereof;

FIG. 4 is a right side view thereof;

FIG. 5 is a front view thereof;

FIG. 6 is a rear view thereof;

FIG. 7 is a top view thereof; and,

FIG. 8 is a bottom view thereof.

The broken lines in the drawings show portions of the magnifying lens and form no part of the claimed design. The additional broken lines in FIG. 1 show an LED light stand and form no part of the claimed design.
